UNITED STATES PATENT OFFICE

129,568

DESIGN FOR A BICYCLE FRAME JOINT OR SIMILAR ARTICLE

Herman L. Kraeft, Cleveland Heights, Ohio, assignor to The Murray-Ohio Manufacturing Company, Cleveland, Ohio, a corporation of Ohio

Continuation of application Serial No. 91,225, March 25, 1940. This application May 16, 1941, Serial No. 100,900

Term of patent 7 years

To all whom it may concern:

Be it known that I, Herman L. Kraeft, a citizen of the United States, residing at Cleveland Heights, county of Cuyahoga and State of Ohio, have invented a new, original, and ornamental Design for a Bicycle Frame Joint or Similar Article, of which the following is a specification, reference being had to the accompanying drawing, forming a part thereof.

Fig. 1 is a plan view of a bicycle frame joint embodying my design;

Fig. 2 is a side elevational view of the bicycle frame joint;

Fig. 3 is a longitudinal cross-sectional view, taken on the line 3—3 of Fig. 1, and

Fig. 4 is a transverse cross-sectional view, taken on the line 4—4 of Fig. 2.

This application is a continuation of my co-pending application, Serial No. D-91,225, filed March 25, 1940.

I claim:

The ornamental design for a bicycle frame joint or similar article, substantially as shown.

HERMAN L. KRAEFT.
